RAILWAY SWITCH OPERATING APPARATUS

Filed June 20, 1928

Fig. 2.

INVENTOR,
T. J. O'Meara,
by A. Z. Winall,
His Attorney.

UNITED STATES PATENT OFFICE.

THOMAS J. O'MEARA, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-SWITCH-OPERATING APPARATUS.

Application filed June 20, 1928. Serial No. 286,798.

My invention relates to railway switch operating apparatus, and has for an object the provision of apparatus whereby a switch may be operated by either one of two separate and distinct devices, such as an electric motor and a hand lever without the necessity for means for selectively connecting said devices with the switch.

I will describe one form of apparatus embodying my invention, and will then point out the novel features thereof in claims.

In the accompanying drawing, Fig. 1 is a view showing in vertical cross section one form of apparatus embodying my invention. Fig. 2 is a view showing in front elevation one form of apparatus also embodying my invention for controlling the operation of the hand lever shown in Fig. 1.

Similar reference characters refer to similar parts in each of the views.

Referring first to Fig. 1, the reference character 1 designates a box or casing containing a vertical shaft 4, the lower end of which terminates in a crank 17 provided with a downwardly projecting pin 3. This crank and pin co-operate with suitable apparatus for actuating and locking a railway switch, which apparatus is not shown in the accompanying drawings but may, for example, be similar to the apparatus shown in United States Letters Patent No. 1,293,290, granted to William Zabel on February 4, 1919. In the said patent the crank 55 and pin 58 correspond respectively to the crank 17 and pin 3 in the present disclosure.

A bearing member 2 is mounted to rotate freely on the shaft 4, and projecting upwardly from the upper surface of this member are a plurality of studs 5, each of which constitutes the bearing for a pinion 6. The upper end of each stud 5 is fixed to a plate 7 which rotates freely on a shoulder formed on a gear 12 hereinafter referred to. This plate is in effect a part of the bearing member 2 because of the rigid connection formed by the studs 5. The studs 5 are all equi-distant from the center line of the shaft 4, so that the pinions 6 are concentrically arranged with respect to this shaft. Fixed to the shaft 4 is a gear wheel 8 having external teeth which mesh with the pinions 6. Mounted to rotate freely on the shaft 4 is a second gear wheel 12, having internal gear

teeth 12^a, which also mesh with each of the pinions 6.

A worm gear 9 is rigidly attached to the bearing member 2, and this worm gear meshes with a worm 10 which is operatively connected with an electric motor 11 through the medium of reduction gearing which is indicated by the dash line 26.

The second gear wheel 12 is also provided with teeth 12^b which constitute a bevel gear and which mesh with a second bevel gear 13 fixed to the end of a shaft 14, which is mounted to oscillate in the box or casing 1. The outer end of the shaft 14 is rigidly attached to a hand lever 15.

The operation of the apparatus shown in Fig. 1, is as follows: I will first assume that the hand lever 15 is locked to prevent movement of the shaft 14, and that the electric motor 11 is operated. Rotation of the worm 10 causes the worm gear 9 and the bearing member 2 to rotate, and the bearing member 2 carries with it the pinions 6. Inasmuch as the second gear 12 is locked, the pinions 6 roll on the gear teeth 12^a, and so these pinions cause rotation of gear wheel 8, which is fixed to the shaft 4, with the result that shaft 4 is rotated to cause operation and locking of the switch.

I will now assume that motor 11 is at rest, and that the hand lever 15 is swung from one extreme position to the other. The consequent rotation of the bevel gear 13 causes gear 12 to turn on the shaft 4, and since the bearing member 2 is held fixed in position, the gear 12 rotates the pinions 6 on their shafts 5, and these pinions in turn rotate the gear 8, which is fixed to the shaft 4, and which, therefore, operates this shaft to actuate and lock the switch.

One feature of my invention is the provision of apparatus permitting independent operation of the switch by either one of two energy sources without the necessity for means for selectively connecting the switch with such sources. As shown in Fig. 1, this is accomplished by planetary gearing for causing rotation of shaft 4 by either the motor 11 or the hand lever 15, but I do not desire to limit my invention to apparatus of this particular type. A similar result may be attained by using differential gearing, or suitably designed mechanical linkage.

It is desirable to prevent operation of the lever 15 except when the railway switch is in one extreme position, such as its normal position, and it is also desirable to prevent the supply of current to the motor 11 when the hand lever 15 is unlocked. I have accordingly provided means for locking the hand lever 15 at all times except when the switch is in the normal position, and for discontinuing the supply of current to the motor 11 when the hand lever is unlocked.

Referring now to Fig. 2, the hand lever 15 normally rests in a yoke 16, and is locked in this yoke by a latch 18 which is pivotally mounted at 18^a in one jaw of the yoke. The latch 18 is eccentrically connected at 20^a with a link 20, which in turn is pivotally connected at 20^b with a locking member 21 provided with a recess 21^a. The locking member 21 operates with a switch locking member 22 which may for example be the slide bar N in the Zabel Patent No. 1,293,290 referred to hereinbefore. The locking member 21 is provided with a dog 23, which co-acts with a roller 24 operatively connected with a circuit controller 25, which circuit controller is included in the circuit for the electric motor 11.

Normally the parts are in the positions in which they are shown in Fig. 2, in which positions the hand lever 15 is locked by the latch 18, circuit controller 25 is closed, and the locking member 21 is out of the path of movement of slide bar 22, so that the railway switch may be operated by the electric motor 11. When the switch is not locked in its normal position, the slide bar 22 is in the path of movement of the locking member 21, so that this member cannot be moved to the left; the result of this is, that latch 18 cannot be opened to release the hand lever 15. When the switch is locked in its normal position, however, the slide bar 22 is withdrawn from the path of the locking member 21, so that latch 18 can then be opened to release the hand lever 15. The opening of the latch 18 causes the locking member 21 to move to the left into such position that the notch 21^a is in the path of movement of the slide bar 22, so that the switch may then be reversed. This movement of the locking member 21 also moves the dog 23 away from the roller 24, so that circuit controller 25 opens and prevents the supply of current to motor 11. Operation of the hand lever 15 will, of course, cause operation of the railway switch, and will also cause the slide bar 22 to move into the notch 21^a in member 21. This prevents the restoring of latch 18 and the closing of contact 25 until the lever 15 and the switch are returned to their full normal locked position, that is, until the full cycle of hand operation has been completed. After the hand lever is restored to its normal position, it may again be locked in this position by closing latch 18, whereupon the slide bar 22 is again released and circuit con-

troller 25 is again closed, so that the parts are restored to the conditions wherein the switch may be operated by the motor 11.

The yoke 16 is preferably provided with a hole 19 to receive a padlock whereby the opening of the latch 18 by unauthorized persons can be prevented.

Although I have herein shown and described only one form of apparatus embodying my invention, it is understood that various changes and modifications may be made therein within the scope of the appended claims without departing from the spirit and scope of my invention.

Having thus described my invention, what I claim is:

1. Railway switch actuating mechanism comprising a rotatable switch operating shaft, a gear fixed to said shaft, a member freely mounted on said shaft, a plurality of pinions rotatably supported by said member and each meshing with said gear, a second gear freely mounted on said shaft and meshing with each of said pinions, and separate and distinct devices for rotating said member and said second gear.

2. Railway switch actuating mechanism comprising a rotatable switch operating shaft, a gear fixed to said shaft, a member freely mounted on said shaft, a plurality of pinions rotatably supported by said member and each meshing with said gear, a second gear freely mounted on said shaft and meshing with each of said pinions, an electric motor operatively connected with said member, and a hand lever operatively connected with said second gear.

3. Railway switch actuating mechanism comprising a rotatable switch operating shaft, an electric motor, a hand lever, and means including planetary gearing or causing rotation of said shaft by either said motor or said hand lever.

4. Railway switch actuating mechanism comprising a gear operatively connected with the switch, a pinion meshing with said gear, a second gear meshing with said pinion, and separate and distinct devices for moving said pinion and said second gear.

5. Railway switch actuating mechanism comprising a gear operatively connected with the switch, a pinion meshing with said gear, a second gear meshing with said pinion, an electric motor for moving said pinion, and a hand lever for rotating said second gear.

6. Railway switch actuating mechanism comprising a rotatable switch actuating shaft, a gear fixed to said shaft and having external teeth, a member freely mounted on said shaft, a plurality of pinions rotatably supported by said member and each meshing with the teeth of said first gear, a second gear freely mounted on said shaft and having internal teeth meshing with each of said pinions, and separate and distinct de-

vices for rotating said member and said second gear.

7. Railway switch actuating mechanism comprising a rotatable switch actuating shaft, a gear fixed to said shaft and having external teeth, a member freely mounted on said shaft, a plurality of pinions rotatably supported by said member and each meshing with the teeth of said first gear, a second gear freely mounted on said shaft and having internal teeth meshing with each of said pinions, an electric motor operatively connected with said member, and a hand lever operatively connected with said second gear.

15 8. Railway switch actuating mechanism comprising an electric motor and a hand lever for operating the switch, and means for preventing operation of said hand lever unless the switch is in one extreme position 20 of its movement.

9. Railway switch actuating mechanism comprising an electric motor and a hand lever for operating the switch, a latch for preventing operation of said hand lever, a 25 circuit controller for governing the circuit for said motor, and means controlled by said latch for opening said circuit controller when the latch is actuated to release said lever.

10. Railway switch actuating mechanism 30 comprising an electric motor and a hand lever for operating the switch, a latch for preventing operation of said hand lever, means for preventing operation of said latch to release said lever unless the switch is in one

extreme position of its movement, a circuit 35 controller for governing the circuit for said motor, and means controlled by said latch for opening said circuit controller when the latch is actuated to release said lever.

11. Railway switch actuating mechanism 40 comprising an electric motor and a hand lever for operating the switch, means for preventing operation of said hand lever unless the switch is in one extreme position 45 of its movement, and means for preventing operation of said motor when said hand lever is unlocked.

12. Railway switch actuating mechanism comprising an electric motor and a hand lever for operating the switch, a latch for preventing 50 operation of said hand lever, and a member operatively connected with the switch and co-acting with said latch to prevent release of the latch to either lock or unlock the hand lever unless the switch is in one extreme 55 position of its movement.

13. Railway switch actuating mechanism comprising a switch actuating member, two separate and distinct devices for causing operation of said member, and means interposed 60 between said devices and said member for permitting said devices to be independently used to actuate the switch without the necessity for means for selectively connecting 65 said devices with said member.

In testimony whereof I affix my signature.

THOMAS J. O'MEARA.
